PORTABLE CORD AND ROPE STORAGE RACK

Gilbert A. Dyal, 4715 W. Anton Road,
Tucson, Ariz. 85706

Filed Jan. 28, 1974, Ser. No. 437,046

Term of patent 14 years

Int. Cl. D8—99

U.S. Cl. D8—220

The figure shown on the accompanying drawing is a perspective view of the portable cord and rope storage rack, the side opposite having a similar appearance.

I claim:

The ornamental design for a portable cord and rope storage rack, as shown and described.
